127,391

DESIGN FOR A FLUORESCENT LIGHTING FIXTURE

Hugh J. Claspy, Monaca, Pa., assignor to The
Phoenix Glass Company, Monaca, Pa., a cor-
poration of West Virginia

Application October 4, 1940, Serial No. 95,643

Term of patent 14 years

To all whom it may concern:

Be it known that I, Hugh J. Claspy, a citizen
of the United States and resident of Monaca,
Beaver County, in the State of Pennsylvania,
have invented a new, original, and ornamental
Design for a Fluorescent Lighting Fixture, of
which the following is a specification, reference
being had to the accompanying drawing, forming
a part thereof.

In the drawing:

Figure 1 is a view in perspective of the fluores-
cent lighting fixture showing my new design.

Figure 2 is an enlarged cross-sectional view
taken on the line 2—2 of Fig. 1. The fixture
end not shown is the same as the end shown.

I claim:

The ornamental design for a fluorescent light-
ing fixture, substantially as shown and described.

HUGH J. CLASPY.
